CLAIM

The ornamental design for a scope for a rifle bore, as shown and described.

DESCRIPTION

FIG. 1 is a front, top and side perspective view of the scope for a rifle bore showing my new design; FIG. 2 is a front elevational view thereof; FIG. 3 is a rear elevational view thereof; FIG. 4 is a side elevational view thereof, the side opposite being a mirror image of the side shown in FIG. 4; FIG. 5 is a top plan view thereof; and, FIG. 6 is a bottom plan view thereof.

FIG. 1

FIG. 4

FIG. 3

FIG. 2

FIG. 5

FIG. 6
